SHUTTLE DRIVE FOR LOOMS

Daniel E. Houghton, Washington, D. C., assignor,
by mesne assignments, to New York Wire Cloth
Company, York, Pa., a corporation of Delaware

Application March 15, 1950, Serial No. 149,825

6 Claims. (Cl. 139—141)

1

This invention relates to new methods for driving the shuttle of a loom and new mechanisms for accomplishing these methods. More particularly, it is concerned with a new method for passing a shuttle through the shed of a loom by means of shuttle bars and a new type of mechanism particularly well adapted to accomplish the new method of driving the shuttle bars.

Discussion of field of invention

In the operation of looms for the weaving of cloth, various factors limit the speed at which the shuttle may be transported across the shed of the loom. One of the major factors limiting this speed of operation is the strain which is placed upon the filling, because of shuttle acceleration. Thus, as the speed of the loom is increased, the point is reached, sometimes referred to as the threshold breaking point, at which the acceleration during some portion of the travel of the shuttle is so high, that so great a stress is placed upon the filling that the tensile strength of the filling is exceeded and the filling breaks.

Several methods of weaving and new improvements in looms have been devised for permitting the shuttle to be picked at greater velocity than is possible without the use of these new methods or new mechanisms, while, at the same time, decreasing the effect of shuttle acceleration, so as to permit the loom to be operated at increased speeds before the threshold breaking point of the filling is reached. Examples of such new improvements are described in my copending applications, Serial No. 113,382, filed August 31, 1949, entitled "Looms for Weaving," and Serial No. 113,381, filed August 31, 1949, entitled "Loom Shuttle Devices" now Patent No. 2,534,598.

This present invention relates to still further new methods for operation of looms which permit higher rates of operation without breakage of the filling and to new mechanisms for driving shuttle bars so as to accomplish these new weaving methods. The invention is particularly adaptable to the art of wire cloth weaving and to the looms now widely used in the industry for this purpose.

Objects

A principal object of this invention is the provision of a new method for passing the shuttle through the shed of a loom and the provision of new improvements in loom structures making possible these methods of loom operation.

Further objects include:

(1) The provision of new loom structures which make possible higher rates of weaving than has

2

been possible heretofore on comparable looms which do not incorporate the new improvements of this invention;

(2) The provision of new methods and new mechanisms for use in conjunction therewith for reducing the strain imparted to the filling during the picking operation in wire cloth looms;

(3) The provision of new shuttle bar drive mechanisms which make possible reduction in strain upon the filling during the picking step for any given speed of weaving;

(4) The provision of a new method for the transfer of the shuttle in a loom from one shuttle bar to another which decreases the rate of change of acceleration of the shuttle during the transfer of the shuttle from one shuttle bar to another, whereby the picking step may take place at a higher average speed for any given stress imparted to the filling;

(5) The provision of new methods and loom mechanisms particularly useful in the weaving of wire cloth.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

General description

These objects are accomplished according to the present invention by a new process for loom operation in which a shuttle is driven through the shed of the loom by a shuttle bar with the shuttle being passed on to the second and opposite shuttle bar before the delivering shuttle bar has reached the end of its travel and when the second shuttle bar is in motion of return to the selvage and withdrawing the empty shuttle bar with a greater speed than it is driven into the shed.

This new method of driving a shuttle through the shed of a loom can be accomplished by various means. However, the preferred means, according to the present invention for accomplishing this, comprises pivoting a pair of pendulous elements to a loom frame at a common point substantially above the center of the lay, connecting the lower free end of the pendulous elements separately to shuttle bars slidably mounted upon

35

40

45

50

55

opposite sides of the loom frame by connecting means and driving the pendulous elements by means of a pair of cranks fixed at an obtuse angle to one another and mounted for oscillation in an arc with the outer end of each crank being movably connected to a separate one of said pendulous elements for travel longitudinally along the respective element when the crank is oscillated through its arc of movement.

The success of the present invention is due primarily to the discovery that when the shuttle bars of a loom are driven in the fashion indicated above, the rate of change of acceleration of the shuttle, particularly at and about the time when the shuttle is transferred from one shuttle bar to another, is decreased, as compared with methods of transfer of the shuttle used heretofore, so that the shuttle may be passed through the loom shed at a greater average speed without reaching the same maximum value of acceleration realized with the operation of looms not operated in accordance with the present invention and the shuttle may be picked without imparting as great a stress to the filling.

Detailed description

A more complete understanding of the new methods and apparatus for use therewith of this invention may be had by reference to the accompanying drawings, in which

Figure 1 is an end view of the lay portion of a loom incorporating the new shuttle bar drive mechanisms of this invention.

Figure 2 is an enlarged, fragmentary view of the portion of the loom shown in Figure 1;

Figure 3 is a side view of the apparatus shown in Figure 2, taken along the line 3—3 of Figure 2;

Figure 4 is an enlarged, fragmentary end view of a section of the mechanism shown in Figure 1, illustrating the details of construction of the connecting rod and shuttle bar portions;

Figure 5 is a top sectional view of the mechanism shown in Figure 4, taken along the line 5—5 of Figure 4;

Figure 6 is an enlarged sectional view of the movable connection between the crank and pendulous element, taken along the line 6—6 of Figure 2;

Figure 7 is an enlarged sectional view of the roller guide mechanism for the pendulous element of the shuttle bar drive, taken along the line 7—7 of Figure 2;

Figure 8 is a diagrammatic illustration of the shuttle bars and drive mechanism in the position when the shuttle has just started to enter the shed from the left-hand side;

Figure 9 diagrammatically illustrates the position of the shuttle drive components just before transfer of the shuttle;

Figure 10 shows the position of the loom components at the moment of transfer of the shuttle;

Figure 11 illustrates the position of the loom components just after the shuttle has passed from the delivering shuttle bar to the receiving shuttle bar;

Figure 12 illustrates the position of the components at the conclusion of the picking operation with the shuttle all the way to the right.

Referring in detail to the drawings, the new apparatus consists fundamentally of a frame 2, pendulous elements 4, cranks 6, crank driving means 8, connecting rods 10, and shuttle bars 12.

The frame 2 can be of any standard variety and in the form illustrated, comprises side members

14, top members 16, cross member 18, lays 20 and 21, and reeds 22.

The pendulous elements or lever arms 4 comprise rigid webs 24, pivoted at the top end 26 on the bolt 28 which is journalled in the bracket 30 which, in turn, is fastened by bolts 32 to the top frame member 16. The lower free ends 34 of the webs 24 are provided with a series of holes 36 to receive clevis pins of the connecting rods 10, as will be more fully described hereinafter. The central portion of the webs 24 are provided with longitudinal slots 38.

Bolted to the cross member 18 by bolts 40 there is a support member 42 which is provided at the lower end 44 thereof with a guide unit 46 consisting of a pair of channel members 48 fastened by the bolts 50 to the lower end 44 of the support member 42. Two such guide units are provided, one for each of the separate pendulous elements 4.

One of each of the cranks 6 is fastened, such as by bolts or rivets 52, to one of a pair of chain wheels 54 which is carried upon the shaft 56, which, in turn, is journalled on the support member 42 with one of the chain wheels on either side of the support member 42.

The chain 58 passes around one of the chain wheels 54, under the sheaves 60 and over the sheaves 62 in normal fashion for connection to the drive mechanisms of the loom (not shown).

The free ends of the cranks 6 are provided with rollers 64 which are fixed on the cranks by means of pins 66. These rollers roll in the slots 38 so that when the cranks are driven through their arc of movement by the crank driving means 8, comprising the chain wheels 54 and chain 58, the rollers move longitudinally along the slot 38 of the lever arms 4 (this can best be seen by reference to Figures 2 and 6 of the drawing).

Toward the lower part of the lever arms 4, there are attached guide rollers 68 journalled on the axles 70 which are carried by the brackets 72 fastened by bolts 74 to the web 24. As can be seen from Figures 2 and 3, these guide rollers fit between the two channel members 48 and serve to keep the lever arms 4 swinging in parallel planes during the operation of the shuttle drive mechanisms.

The connecting means 10 consist of a pitman 76 provided on the inner end with a clevis 78 which fits over the lever arms 4. Clevis pins 80 extend through the clevis 78 and through the desired opening 36 in the arms 4, thus operatively connecting the means 10 to the arms 4.

The outside ends of the pitman 76 are provided with outside threaded elements 82 to which the lug 84, extending from the shuttle bar 12, is adjustably fastened by means of the nuts 86.

The shuttle bars 12 are slidably carried upon the lay 20 by means of the bracket 88. The inner end 90 of the shuttle bars is provided with shuttle grasping and engaging means 92 which are operated for connection with and release of the shuttle by means of the operating unit 94. This unit consists of a pair of lever members 96, pivoted at one end 98 to the bar 12 and at the other end 100 to the roller 102 and the lever member 104 which, in turn, is pivoted at the opposite end to the rod clamp 108. The rod clamp 108 is adjustably fastened to the rod 110, which is slidably in bar 12, by means of the screw 112.

Engagement of the rollers 102 with the cam members 106 upon passage of the bar 12 into the shed forces the rod 110 outwardly from the

end 90 of the bar 12, thus operating the shuttle release mechanism in known fashion.

Operation

With a conception of the relationship of the various parts of mechanism of this invention in mind, from the description given above, the operation thereof can now be described in conjunction with Figures 8 to 12, giving a better idea of the new method of operation of looms as provided by this invention.

With the shuttle 114 in position in left-hand shuttle bar 12 downward movement of the respective crank 6 begins the drive of the shuttle into the shed of the loom (see Figure 8). As the shuttle bar proceeds further into the shed, the shuttle increases in acceleration as it passes the selvage and until it reaches approximately the center point of the lay. At the same time, the opposing shuttle bar enters the loom to meet the incoming shuttle, but it passes its point of maximum movement into the shed before meeting the incoming shuttle, so that it begins its return movement before picking up the shuttle from the first shuttle bar.

As can be seen from Figures 8 to 10, while the empty carrier is making its stroke into the shed, the cranks move 120° and, while the shuttle is being brought to the center, the cranks move 165°. During the interval between the end of the "in" stroke of the empty carrier and the exchange of the shuttle, the empty carrier reverses its direction of motion and increases its speed, going out of the shed at an average speed greater than it enters with, so that at the time the shuttle is exchanged, the two carriers are moving at the same speed and in the same direction. In this way, the shuttle is passed at a time when the shuttle bar which brought it into the shed is just starting to slow down and the one which is receiving it has speeded up to the same speed on the return motion of this shuttle bar. The drop in acceleration of the shuttle at the exact moment of transfer from one to another is considerably less than the drop in acceleration experienced by shuttles passed as in methods of weaving used heretofore. After the shuttle is carried beyond the selvage on the opposite side by the second shuttle bar, a selvage loop is formed in the filling and the picking, as described, is repeated.

As can be seen from the detailed description given above, a new method of picking the shuttle across the shed of a loom and new apparatus for accomplishing this new method have been provided by the present invention. As a matter of fact, actual operations on standard weaving looms in wire cloth weaving establishments have shown that the shuttle may safely operate at about 80 picks per minute, using the new methods and procedures of this invention, as compared with a maximum safe speed of about 65 picks obtained with the best drive mechanisms known heretofore. These new methods and apparatus make possible the operation of looms at higher speeds, so that a greater amount of woven goods can be turned out per machine for any given period of operation. It will be clear to those skilled in the art that other apparatus may be employed to accomplish the new methods of shuttle driving, as described herein, and that the preferred type of mechanism for this purpose, as disclosed above, can be altered in various respects by substitution of mechanical equivalents for the particular elements illustrated and described. For example, a slide and slide way arrangement

can be substituted for the roller 64 and slot 38, as described above, and similar substitutions may be made. Accordingly, the novel principles of this invention are broader than the specific embodiments recited above and rather than unduly extend this disclosure by attempting to list all the numerous modifications which have been conceived and reduced to practice during the course of this development, these novel features are defined in the following claims.

I claim:

1. A loom comprising a frame, a shuttle bar slidably carried by the frame on each side thereof, a pair of pendulous elements pivoted at a common point above said bars for swinging movement parallel to one another, means connecting a bar on each side of the frame to the unpivoted end of one of said elements, a pair of cranks fixed at an obtuse angle to one another for oscillation in an arc in a plane parallel to the plane of swinging of said elements, a movable connection between each one of said cranks and a separate one of said elements whereby the end of each crank reciprocates longitudinally along its respective pendulous element when oscillated in said arc, and means for driving said cranks in said arc.
2. A shuttle drive mechanism for looms comprising in combination a pair of opposed shuttle bars having means on one end for releasably engaging a shuttle and having the other end attached to a connecting rod, a pair of lever arms pivoted at a common point above the loom reeds, with the other ends of said arms each being connected to one of said connecting rods, a longitudinal slot in each of said lever arms, a chain wheel journaled to rotate in a plane parallel to the plane of movement of said lever arms and cranks carried by said chain wheel, each of said cranks having a portion of its outer end positioned for oscillation in the slot of one of said lever arms.
3. A shuttle drive mechanism for looms comprising in combination a pair of shuttle bars slidably mounted on opposite sides of the loom, a connecting rod pivoted to the outside end of a shuttle bar on each side of the loom, a pair of lever arms pivoted at a common point above the loom reeds for swinging movement in planes parallel to one another, the inside end of each connecting rod being pivoted to the lower end of a respective lever arm, a chain wheel journaled above the loom reeds and below said lever arm pivot point between said lever arms in a plane parallel to the planes of movement of said lever arms, a longitudinal slot in each of said lever arms located approximately midway in the arm, a pair of cranks fastened to said chain wheel at an obtuse angle to one another, an operative connection between the free end of each crank arm and its respective lever arm slot, whereby said free end oscillates along said slot when moved in a circular path by the chain wheel and means for rotating said chain wheel.
4. A mechanism as claimed in claim 3, wherein in said crank arms are provided at their free end with rollers which roll in the longitudinal slots of the lever arms.
5. A mechanism as claimed in claim 3, wherein in said lever arms are provided with rollers which roll in guide ways carried by the loom frame in line with the path of swinging movement of the lever arm guiding the roller so that the lever arm is guided thereby during its movement.
6. A mechanism as claimed in claim 3, where-

in said connecting rods are pivoted to said lever arms by clevis pins and said lever arms are provided with a series of holes to receive the pins whereby adjustment can be made in the length of travel of the connecting rod upon operation of the lever arms by choice of the lever arm hole to which the connecting rod is attached.

DANIEL E. HOUGHTON.
